CATALYTIC CONVERSION OF
HYDROCARBON OILS

du Bois Eastman and Charles Richker, Port Arthur, Tex., assignors, by mesne assignments, to The Texas Company, New York, N. Y., a corporation of Delaware

Application March 18, 1941, Serial No. 383,900

5 Claims. (Cl. 196—52)

This invention relates to the catalytic conversion of heavier hydrocarbon oils to convert them to gasoline hydrocarbons suitable for motor fuel.

The invention broadly contemplates a process in which the catalytic reaction is effected at elevated temperature and in which the hydrocarbons to be converted are raised to the catalytic reaction temperature in a heating zone under such controlled conditions of heating that the oil upon coming into initial contact with the catalyst is substantially free from bodies which are readily converted to carbon or coke upon contact with the catalyst. The so heated oil is then passed to a catalytic reaction zone advantageously without delay during which undesired non-catalytic reactions might occur.

It has been proposed in the prior art relating to cracking of oil to heat the oil rapidly to a cracking temperature without substantial cracking occurring and thereafter passing the heated oil to a reaction zone wherein the reaction is effected without the addition of further heat. The object heretofore was to avoid the deposition of carbon in the heating coil which deposition caused localized overheating of the coil resulting in splitting the heating coil upon continued exposure to heating.

We have found, however, that even though the oil feed to a catalytic cracking reaction is heated under conditions such that no carbon formation occurs in the heating coil or heating zone nevertheless the conditions of heating may still be so severe that hydrocarbon products are formed which are highly susceptible to carbon formation upon contact with a solid pulverulent porous adsorptive type of conversion catalyst. The carbon forming bodies so formed appear to be readily capable of conversion to carbon in the presence of the catalyst, and much more so than in the absence of the catalyst even with continued exposure to elevated temperature.

Therefore, an important object of the invention is to avoid the existence of conditions within the heating zone which would result in thermal conversion.

A further object is to avoid such thermal reactions thereby materially reducing the deposition of carbonaceous material upon the catalyst in the catalytic reaction zone.

In catalytic cracking processes as heretofore used commercially it has been customary to pass a preheated stream of the oil in substantially vaporized form through a catalyst bed maintained at an elevated temperature for a comparatively short conversion time to convert the oil to gaso-

line hydrocarbons with concomitant breakdown of a portion of the feed to gas and resultant deposition of coke or carbon on the catalyst. The activity of the catalyst, as measured by the percentage conversion to gasoline and gas, drops off exceedingly rapidly and at the same time the carbon deposit builds up on the catalyst. In order to maintain a desirably high conversion it has been customary to run with an exceedingly short conversion period or onstream time, then terminate the flow of the hydrocarbon charge through the catalyst bed and reactivate that bed by passing therethrough a highly heated gas containing air or oxygen to burn off the carbon deposits and bring the catalyst back to a high activity. In such operations it has been customary to employ an operating procedure such that the catalyst cracking chamber is offstream for at least twice the period of time that it is onstream or is actually being used for the conversion operation.

It was thought necessary to use a short intermittent conversion period of this type in order to obtain commercially satisfactory results from the standpoint of yield and quality of product. It was believed that continuance of the onstream time would give a progressive decrease in conversion, while the rate of carbon deposition on the catalyst would remain essentially constant under given operating conditions; and also it was known that when excessive quantities of carbon were deposited on the catalyst bed the reactivation could only be accomplished with exceedingly great difficulty and often without a return of the catalyst to a desired high activity. For these reasons resort had been made to short onstream periods.

However, as disclosed in our co-pending application, Serial No. 313,654, filed January 13, 1940, now U. S. 2,319,590, it has been found that contrary to the previous knowledge, greatly improved results are secured under proper and controlled operating conditions by employing a conversion period or onstream time which is increased many times over previous practice. Further the proper reactivation of the catalyst is effected with a reactivation period which is not greater than and is usually less than the conversion period. Greatly increased throughput and higher efficiency of operation of the plant are thereby secured.

As disclosed in our aforementioned pending application these improved results are accomplished by: (1) selecting a charging stock, preferably relatively free from unsaturated constituents, which is relatively clean and of good color, namely, having a carbon residue of less than 0.2% and a

color of less than 200 as measured on the Lovibond scale using a $\frac{1}{2}$ inch cell; (2) employing a cracking catalyst of high and sustained activity; and (3) correlating the operating conditions of temperature, pressure and space velocity with other factors to allow prolonging the conversion time to a period not less than one hour and preferably of the order of 8 to 20 hours or more.

It was found that under these conditions the catalyst with deposited carbon or coke at the termination of the onstream time can be reactivated without difficulty with a reactivation period not greater than 4 hours and generally of the order of 2 to 3 hours. It was also found that under these conditions the conversion rate drops off only a comparatively small amount as the conversion period is prolonged to within the range set forth above, while the rate of carbon deposition on the catalyst falls off a comparatively large amount. Conversion yields in excess of 50 pounds and generally of the order of 80 pounds or more of gasoline plus gas per pound of carbon deposited on the catalyst are obtained. At the same time the ratio of gasoline to gas produced is maintained at a desirably high figure and the quality of the gasoline is at least as good as that produced with the short conversion period.

In accordance with the present invention we have found that while selection of the feed stock is important, nevertheless the character of the heated stock just prior to initial contact with the catalyst is also important. Seemingly, the heated stock should be substantially free from certain highly unstable bodies having pronounced coke forming tendencies and which are formed where the oil has been subjected to severe conditions of heating. We have found that the tendency of a given stock to decompose into carbon on contact with the catalyst may be largely inhibited provided suitably controlled conditions prevail in the heating zone.

Desirable conditions of heating exist when the oil undergoes no change in composition as indicated, for example, by the absence of any reduction in its flash point as the result of the heating in the heating zone.

The severity of thermal conditions prevailing within a given heating coil can be indicated by determining the "soaking volume factor" of the heater employed and we have found that in accordance with this invention the feed oil should be raised to the catalytic reaction temperature by heating under conditions such that the "soaking volume factor" should not exceed about 1.0 and is preferably as low as possible, in the range 0.05 and below.

Experiments with oil of carbon residue and color characteristics, as previously described, indicate that when the "soaking volume factor" has a value of about 1.0 the carbonaceous deposit on the catalyst is about 1 to 2% by weight of the feed oil passed to the catalytic reaction zone. On the other hand, when the "soaking volume factor" is about 0.05 the carbonaceous deposit is reduced to about 0.3 to 0.5% by weight of the charge.

The equation for the "soaking volume factor" is

$$F = \frac{1}{L} \int_{V \text{ where } t=800^\circ \text{ F.}}^{V \text{ where } t=\text{outlet temperature}} R \times Y \times dV$$

where

F = "soaking volume factor" of that portion of the heating coil wherein the oil is at a temperature of 800° F. and above;

L = barrels per day of liquid oil through the coil measured at 60° F. ;

t = the temperature of the oil $^\circ \text{ F.}$ along the coil between the point where the oil is at a temperature of 800° F. and the point at which the oil is discharged—this outlet temperature, as indicated in Figure 1, may be as high as 1150° F. ;

V = the internal volume in cubic feet of the coil between the points where t equals 800° F. and t equals the discharge outlet temperature;

$$R = \text{antilog } (16.3108 - \frac{20550}{t+460})$$

15 Y (for pressures below 100 pounds per square inch gauge) = $\text{antilog}_{10}(.8929 \log_{10}P - 1.7858)$;
 Y (for pressures above 100 pounds per square inch gauge) = $\text{antilog}_{10}(1.709 \log_{10}P - 3.418)$;
 and

20 P = pressure in pounds per square inch gauge along the coil between the points where t equals 800° F. and t equals oil outlet temperature.

Hereinafter the portion of the heating coil between the point where the oil temperature t equals 800° F. and the point where t equals outlet temperature will be referred to as the V portion of the coil for convenience.

25 In an actual heating coil the temperature progressively increases while the pressure progressively decreases toward the outlet. Therefore, the reaction constant K must vary with the temperature throughout the coil so that the effective value of "soaking volume factor" F is an integration of the values of the soaking volume factor for small sections of the heater.

30 Also the vapor being heated in the V portion of the coil is in that portion of the coil a long or short time depending on whether the pressure is high or low. Accordingly a given temperature range with a given feed rate produces greater cracking in the heating coil at high pressure than at low pressure. Therefore it is necessary to employ a pressure correction factor Y .

35 45 It is generally accepted in the art that the relationship between the reaction velocity constant and temperature may be expressed by the Arrhenius equation which is:

$$K = \alpha e^{-E/\rho T}$$

50 where

E is the energy of activation in B. t. u. per 1 pound mol;

ρ is the gas law constant, namely, 1.9864 B. t. u. per 1 pound mol per $^\circ \text{ F.}$ absolute;

T is the temperature in $^\circ \text{ F.}$ absolute;

α is some constant;

e is the Naperian base, 2.71828

60 65 The constant α in the equation varies for different stocks, while E , the energy of activation, is essentially the same for all stocks as explained in the article by Geniesse and Reuter entitled "Reaction-velocity constants of oil cracking," Industrial Engineering Chemistry, vol. 24, No. 2, pages 219-222, 1932. Since this is the case the ratio of the reaction velocity constant at any given temperature to that at any other temperature is approximately the same for all cracking stocks.

70 These authors determined E as having a value of 53,400 gram calories per gram mol (equivalent to 96,120 B. t. u. per pound mol), but calculations based on more recent data indicate a value of 94,000 B. t. u. per pound mol.

75 For practical purposes a base temperature of

800° F. is conveniently chosen as a base temperature in the ordinary coil heater wherein the oil is exposed to elevated temperatures momentarily.

The ratio R as defined above is equal to

$$\frac{K_t}{K_{800^\circ F.}} = \frac{\left(\frac{E}{e}\right) - \frac{E}{\rho(t+460)}}{\left(\frac{E}{e}\right) - \frac{E}{\rho(800+460)}}$$

which upon simplification becomes

$$R = e \left(\frac{\frac{E}{\rho(800+460)} - \frac{E}{\rho(t+460)}}{\frac{E}{\rho(800+460)} - \frac{E}{\rho(800+460)}} \right)$$

and which may be written as

$$\log_{10} R = \left[\frac{1}{2.30258} \right] \left[\frac{E}{\rho(800+460)} - \frac{E}{\rho(t+460)} \right]$$

By substituting the numerical values for E and ρ the following equation results:

$$\log_{10} R = 16.3108 - \frac{20550}{t+460}$$

or

$$R = \text{antilog}_{10} \left(16.3108 - \frac{20550}{t+460} \right)$$

The curve in Figure 1 of the drawings shows the relationship between R and temperature over a wide range of temperature, namely, about 800 to 1150° F., and within which range R may have a value ranging from 1 to about 3800 as indicated on the drawings.

In determining the pressure correction factor Y it is first necessary to establish the relationship between the "soaking volume factor" F and the per cent conversion to gasoline in a heating coil in which there is no substantial pressure gradient. Taking the relationship for the 100 pounds per square inch gauge pressure level as a basic or reference pressure level the pressure correction factor is the ratio of the "soaking volume factor" at the reference pressure level to the "soaking volume factor" at any other desired level to give the same per cent conversion to gasoline. The reference pressure level is conveniently chosen as one within or in close proximity to the average pressure prevailing in the V portion of the heating coil.

Gasoline is considered as a product having a 400° F. end point and a Reid vapor pressure value of 9.5 pounds.

The curve in Figure 2 of the drawings represents graphically the relationship between pressure and pressure correction factor Y.

The equation of the curve of Figure 2 for pressures above 100 pounds per square inch gauge may be written as:

$$\log_{10} Y = 1.709 \log_{10} P - 3.418$$

or as

$$Y = \text{antilog}_{10} (1.709 \log_{10} P - 3.418)$$

The equation of the curve for pressures below 100 pounds may be written as:

$$\log_{10} Y = 0.8929 \log_{10} P - 1.7858$$

or as

$$Y = \text{antilog}_{10} (0.8929 \log_{10} P - 1.7858)$$

As previously mentioned the temperature progressively increases through the V portion of the heating coil and therefore it is necessary to determine the temperature gradient in this portion of the coil. This is arrived at by plotting each actual temperature at successive points or

increments in the coil, beginning with the point at which the hydrocarbon is at the chosen base temperature, for example, 800° F., against the corresponding volume of the coil between the point corresponding to the chosen base temperature and each successive temperature point. Curve A in Figure 3A is a typical example.

From Figure 1 the value of R can be determined for each corresponding temperature point on curve A and the values for R can then be plotted as ordinates against the corresponding partial coil volumes as abscissae thereby forming the curve B of Figure 3B. By partial coil volume is meant the volume of the coil between the point corresponding to the base temperature and each successive temperature point. The quotient of the area under the curve of Figure 3B divided by V represents the integrated average of R.

The pressure gradient curve for the V portion of the coil is plotted as curve C of Figure 3C by plotting actual coil pressures at successive points, beginning with that corresponding to the chosen base temperature used in plotting curve A, against the corresponding volume of the coil between the chosen base point and each successive pressure point. From Figure 2 the value of the pressure correction factor Y can be determined for each pressure point on curve C and the values of Y can be plotted as ordinates against the corresponding partial coil volumes as abscissae thereby forming the curve D of Figure 3D. The quotient of the area under the curve of Figure 3D divided by V represents the integrated average of Y.

The R and Y curves are combined to form a consolidated (RY) curve. This is done by selecting a partial coil volume and reading the corresponding values of R and Y. The products of the values of R and Y are plotted against the corresponding partial coil volume points giving the consolidated curve E of Figure 3E.

The area under the curve E is integrated to obtain the product of V(RY) in the above equation. Thus

$$\text{area} = \int_V^{V \text{ where } t = \text{outlet temperature}} R \times Y \times dV$$

so that

$$F = \frac{1}{L} \int_{V \text{ where } t = 800^\circ F.}^{V \text{ where } t = \text{outlet temperature}} R \times Y \times dV$$

In cases where the transfer lines are large and where there is appreciable free space between the heating coil outlet and the catalyst itself, these volumes should be included as a part of the V portion of the coil and the calculation made as described above.

In the foregoing manner the "soaking volume factor" for any given coil heater installation can be determined readily. The preferred heating conditions contemplated by our invention are realized when the "soaking volume factor" does not exceed about 1.0 and is preferably in the range 0.05 and below as previously mentioned.

Oil may be heated under conditions such that there is no substantial cracking as measured by prior art standards. Yet if the heating is under such conditions that the "soaking volume factor" exceeds 1.0 the carbon deposition upon subsequent contact with the cracking catalyst will still be excessive. This is borne out by the following examples.

In these examples the feed oil was a virgin gas oil having an A. P. I. gravity of 37°; a 50% boiling point of about 528° F.; a Conradson carbon content of 0.01%; and derived from Oklahoma crude.

The oil was passed in a continuous stream through a coil heater under a pressure of 50 pounds gauge wherein it was heated to the reaction temperature. The heated oil vapors were passed from the heating oil through a catalytic reactor packed with a catalyst comprising a synthetic silica-alumina-zirconia material.

The onstream period for each reactor extended for a period of 4 hours following which the catalyst was reactivated in the usual manner and again placed onstream, the operation being repeated for 6 cycles at each set of temperature conditions.

During each regenerating period the rate of flow of the oxygen containing regenerating gases fed to the reactor undergoing regeneration was held at a constant measured rate and the composition of the gases entering and leaving the reactor determined at frequent intervals. The quantity of carbonaceous material removed from the catalyst during regeneration was then determined by integrating the increase in carbon monoxide and carbon dioxide content of the gases over the regenerating period and multiplying by the quantity of regenerating gas used. These figures were verified by calculating the carbon deposition from the consumption of oxygen during the regenerating period.

The "soaking volume factor" of the heating coil was varied primarily by increasing the length of the portion of the coil in which the oil was at a temperature above 800° F., thereby increasing the length of time of exposure of the oil to high temperatures.

The following tabulated data provide a comparison of the carbon deposition on the catalyst with different heating conditions prevailing in the heating coil:

	A	B	C	D	E
Average reactor temperature, °F.....	908	943	945	951	955
Soaking volume factor.....	0.024	0.051	0.071	0.216	1.30
Carbon deposited on catalyst, percent by weight of feed oil.....	0.30	0.32	0.88	1.07	1.52
Gasoline ¹ yield, percent by vol. of feed.....	26.8	24.8	28.1	23.6	27.0
Gas yield, percent by weight.....	10.88	11.31	12.44	12.11	16.13

¹ 400° F. end point gasoline having a Reid vapor pressure of 9.5 pounds.

As the foregoing data indicate the carbon deposition becomes quite substantial where the heating coil is operated with a "soaking volume factor" in excess of about 1. Even in run E where carbon deposition on the catalyst was excessive no carbon deposition in the heating coil could be detected.

From the standpoint of economic operation of a catalytic process with long onstream periods, it is desirable that the carbon deposition does not exceed about 1.0% by weight of the feed.

For example, with an operation giving a 20% conversion to gasoline during an 8 hour onstream period it is desirable that the carbon deposition should not exceed about 0.2%. With a 30% conversion it is desirable that the carbon deposition should not exceed 0.3%.

Therefore, in order to realize these conditions it is essential to employ a "soaking volume fac-

tor" which is substantially below 1 and in the range .05 and below.

Factors which may be used to control the "soaking volume factor" in a given operation include:

(1) Injection of steam or other inert diluent such as carbon dioxide in the feed to the heating coil;

(2) Employment of a large ratio of heating surface to volume of heating coil and/or employment of a high rate of heat transfer;

(3) Avoidance of excessive pressure drop through the heating coil; and

(4) Avoidance of localized overheating of the coil.

In the foregoing experiments a synthetic silica-alumina-zirconia type catalyst was used. However, it is contemplated that other catalysts may be employed. Various acid-treated and metal-substituted clays, such as the Super-Filtrols, are satisfactory. Likewise, the acid-treated and metal-substituted natural or artificial zeolites, such as the artificial zeolite known as Doulcill, can be used. Various metals can be substituted in the clays or zeolites, such as uranium, molybdenum, manganese, lead, zinc, zirconium, nickel and the like. Likewise, the combination of certain acid-treated active clays of the character of Filtral, together with added proportions of alumina or silica or both can be employed. Alumina alone may be used under certain conditions. The synthetic silica-alumina catalysts can be improved by the addition of other constituents, such as zirconium oxide or molybdenum oxide. Other catalysts which are not silica-alumina catalysts, either synthetic or prepared from natural minerals, have been found which satisfy the characteristics of the catalyst of the present invention. Examples of other suitable catalysts

comprise metallic halide compounds such as the halides of aluminum and chromium, etc. In general, a catalyst is employed which is stable at high temperatures of the order of 1400 to 1600° F., as determined by calcining in a muffle furnace at that temperature, and which is a measure or indication of the ability of the catalyst to maintain its activity under the customary temperatures of reactivation of the order of 1100 to 1400° F., as measured by thermocouples within the catalyst bed during the reactivation cycle.

It is preferred to employ a catalyst which is substantially free from alkali and alkaline earth metals.

While a stationary catalyst bed has been referred to it is also contemplated that the invention is applicable to other types of catalytic reaction systems including the so-called "fluid" catalyst system wherein a finely powdered catalyst is suspended within the reaction zone in the presence of the hydrocarbons undergoing treatment.

Also if desired the conversion reaction may be carried out in the presence of light gases including hydrogen which may be recirculated through the heating and conversion zones or through the conversion zone only.

Although the invention has particular application in the conversion of gas oil and other high boiling hydrocarbons, it may be employed in effecting catalytic conversion of various types of hydrocarbons at elevated temperatures.

Obviously many modifications and variations of the invention, as hereinbefore set forth, may be made without departing from the spirit and scope thereof, and therefore only such limitations

should be imposed as are indicated in the appended claims.

We claim:

1. In a continuous process for the manufacture of high antiknock gasoline by catalytic conversion of a feed oil at cracking temperatures, the steps which comprise passing a stream of gas oil having a carbon residue less than 0.2% and a color less than 200 on the Lovibond $\frac{1}{2}$ inch cell through a tubular heater, heating the stream therein to a temperature in the range 800 to 1150° F. under conditions such that the "soaking volume factor" (referred to a coil having a pressure characteristic of 100 pounds per square inch gauge) does not exceed 0.05 as determined by 15 the equation:

$$F = \frac{1}{L} \int_{V \text{ where } t=800^{\circ} \text{ F.}}^{V \text{ where } t=\text{outlet temperature}} R \times Y \times dV$$

where

F="soaking volume factor" of that portion of the heating coil wherein the oil is at a temperature of 800° F. and above;

L=barrels per day of liquid oil through the coil measured at 60° F.;

t=the temperature of the oil in °F. along the coil between the point where the oil is at 800° F. and the point at which the oil is discharged from the coil;

V=the internal volume in cubic feet of that portion of the heating zone occupied by oil at a temperature in the range 800° F. and above;

$$R = \text{antilog}_{10} \left(16.3108 - \frac{20550}{t+460} \right)$$

Y (for pressures above 100 pounds) = $\text{antilog}_{10} (1.709 \log_{10} P - 3.418)$;

Y (for pressures below 100 pounds) = $\text{antilog}_{10} (.8929 \log_{10} P - 1.7858)$;

P=pressure in pounds along the coil between the points where t equals 800° F. and t equals the outlet temperature of the oil;

and thereafter subjecting the thus heated oil in vapor form to the action of an active synthetic silica-alumina-zirconia cracking catalyst maintained at a temperature in the range 800° F. and above, thereby effecting substantial conversion of feed oil into gasoline hydrocarbons.

2. The method according to claim 1 in which the "soaking volume factor" is in the range about 0.024 to 0.05.

3. The method according to claim 1 in which the stream of heated oil vapor is passed contin- 55

uously through a stationary mass of the active cracking catalyst for at least about 4 hours without interruption for reactivation of the catalyst.

4. In a continuous process for the manufacture of high anti-knock gasoline by catalytic conversion of a feed oil at cracking temperatures, the steps which comprise passing a stream of gas oil having a carbon residue less than 0.2% and a color less than 200 on the Lovibond $\frac{1}{2}$ -inch cell 10 through a tubular heater, heating the stream therein to a temperature in the range 800 to 1150° F. under conditions such that the "soaking volume factor" (referred to a coil having a pressure characteristic of 100 pounds per square inch gauge) does not exceed 0.05 as determined by the equation:

$$F = \frac{1}{L} \int_{V \text{ where } t=800^{\circ} \text{ F.}}^{V \text{ where } t=\text{outlet temperature}} R \times Y \times dV$$

where

F="soaking volume factor" of that portion of the heating coil wherein the oil is at a temperature of 800° F. and above;

25 L=barrels per day of liquid oil through the coil measured at 60° F.;

t=the temperature of the oil in °F. along the coil between the point where the oil is at 800° F. and the point at which the oil is discharged from the coil;

30 V=the internal volume in cubic feet of that portion of the heating zone occupied by oil at a temperature in the range 800° F. and above;

$$35 R = \text{antilog}_{10} \left(16.3108 - \frac{20550}{t+460} \right)$$

Y (for pressures above 100 pounds) = $\text{antilog}_{10} (1.709 \log_{10} P - 3.418)$;

Y (for pressures below 100 pounds) = $\text{antilog}_{10} (.8929 \log_{10} P - 1.7858)$;

P=pressure in pounds along the coil between the points where t equals 800° F. and t equals the outlet temperature of the oil;

and thereafter subjecting the thus heated oil in vapor form to the action of a solid active cracking catalyst stable at 1400 to 1600° F. and at a temperature in the range 800° F. and above, thereby effecting substantial conversion of feed oil into gasoline hydrocarbons.

45 5. The method according to claim 4 in which the "soaking volume factor" is in the range of about 0.024 to 0.05.

DU BOIS EASTMAN.
CHARLES RICKEE.
